UNITED STATES PATENT OFFICE

SAMUEL C. CUTLER, OF MURRAY HILL, NEW JERSEY

ATOMIZING AND HUMIDIFYING APPARATUS

Application filed May 15, 1928. Serial No. 277,921.

This invention relates to methods of and means for atomizing and the breaking up of liquids such as water.

The general object of the invention is to provide simple and compact apparatus for humidifying air or other gases. The apparatus is arranged to effect the contacting of gases with a liquid broken up in a plurality of forms. In order to obtain maximum efficiency in the humidification and charging of gases, as well as in removing undesirable moisture entrained in the gases, it may be highly advantageous to produce various strata of spray and at times to produce a moisture condition approximating fog. Applicant therefore proposes to provide a combination of apparatus capable of subjecting gases to a plurality of sprays of different fineness. The gases may be passed through strata of spray and fog in succession and with extreme rapidity and a maximum of efficiency, at very low cost and at a minimum of expense, to be thoroughly humidified and saturated for any given temperature.

A feature of the invention resides in the provision of a series of pumps arranged to discharge a plurality of streams of spray at different levels within a humidifying apparatus. Means in combination with the pumps are suitably located in the path of the spray and designed to further break it up into finer particles. As a result any of the pumps may be used to produce sheet spray and mist at the same time. The auxiliary apparatus for producing particles of greater fineness may, if desired, be variously positioned in the path of the gases passing through the device.

A further feature resides in the provision of baffle means arranged to control the movement of gases through the device and route them into the paths of the spray and mist. The baffle means serves a dual purpose in that its lower periphery is formed as a serrated petticoat having a plurality of units radially positioned with respect to the axis of the pump. The pump is suitably mounted on a shaft and adapted to throw a spray in a plane substantially perpendicular to the units which thereupon atomize the comparatively

large globules of moisture into infinitesimal particles.

A further feature covers the arrangement of the pump whereby a train of liquid will be elevated on both the inner and outer surfaces of the pump and impinge over a multi-edged apron integral with and formed as part of the periphery of the pump. As a result, a finer spray will be produced as well as two sheets of spray by the one pump. Auxiliary means for further breaking up the spray may here also be provided to produce a fog so fine that its absorption by unsaturated gases, notwithstanding their degree of saturation, will be immediate.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a section through a device incorporating one form of the invention;

Fig. 2 is a similar section illustrating the combination of a plurality of pumps with auxiliary means for breaking up spray into a mist;

Fig. 3 is a detail of a pump in combination with auxiliary baffles, showing the production of spray on one side of the baffles and mist on the other side;

Fig. 4 is a detail of one form of pump; and

Fig. 5 shows a pump of different design in which an integral apron throws a plurality of sprays to be further broken up by auxiliary baffles.

Considering all the figures simultaneously, similar designations referring to similar parts, numeral 6 illustrates a suitable humidifying device. The device may be made in various sizes for industrial purposes, or in small compact form for use as a home humidifier. In the form shown in Fig. 1, the device is provided with a motor 7 suitably attached to top 8 which encloses the device. Bottom

9 may be formed so that sides 10 fit therein, as illustrated, and the upper periphery of the sides may be turned to better mount the top. The periphery also supports a partition wall 11 having its lower edge in the form of a series of baffles 12. The motor shaft mounts fan 13 and spider 14 to which is secured pump 15. The pump may be formed as illustrated conically in shape with a substantially flat and elongated surface periphery. A supply of water or other liquid may be suitably connected to maintain a desired level in the bottom of the device. The device may also be equipped with a heating coil 16 to temper the liquid.

15 The side walls are provided with openings 17 and the top covering has exhaust openings 18. When the motor is started, the rotation of the pump will cause the water to be drawn 20 through opening 19 up the sides of the pump and due to the centrifugal force, discharged from the periphery of the pump. The water will leave the periphery in the form of a sheet which immediately breaks up into spray 25 20.

25 The baffles are formed with their surfaces preferably radially disposed with respect to the axis of the pump. Inasmuch as similar parts of partition 11 are concentric with respect to the axis of the pump, each of the baffles is equi-distant from the axis and periphery of the pump. The spray, therefore, impinges against baffles 20 with equal force to effect an identical result at every point of 30 contact with the baffles.

35 As illustrated in Fig. 1, the liquid whirled from the periphery is in the form of a spray 20. However, upon contacting with the radially disposed baffles the spray will be further broken up into the form of a fog or 40 mist 21. While the baffles in Fig. 1 are shown substantially flat and radially disposed with respect to the pump axis, they may be variously designed to produce disintegration of 45 the particles of water in spray 20 to a desired degree of fineness.

50 In operation, the gas such as air will be drawn within the device through intake ports 17 due to the action of fan 13. As illustrated, 55 the gas will be routed between side walls 10 of the device and partition 11 and hence forced through mist 21. After passing through the mist the action of the fan draws the gases through spray 20 within the partition wall 11 and out from the device through 60 exhaust ports 18. Since the mist or fog 21 is extremely fine a maximum of absorption by the gases will take place as they pass through this mist. The further passage of the gases 65 through the spray serves to clear them of entrained moisture by flocculation. The heavier the sheet of spray the less entrained moisture will remain in the gases. It is of note also that by varying the opening 19 in 70 the bottom of the pump the amount of mois-

ture entrained in the air can be varied and consequently controlled.

75 In Fig. 2 the arrangement comprises a series of pumps 15 suitably attached to spider 14 mounted on the shaft of motor 7, on which is also mounted fan 13. The pumps 15 are variously designed to draw water on the inner or both surfaces of each of them. In the arrangement of Fig. 2 the pumps are illustrated as adapted to pull a stream on their inner surfaces, to be whirled from their peripheries in the form of sheet spray 20. It is evident that any number of sheets of spray can be thus produced depending upon the number of pumps. Applicant has successfully used a series of nine pumps. To further effect the breaking up of spray 20, baffles 12^a are suitably positioned about the periphery of the lowest of the pumps shown in Fig. 2. The baffles completely surround the periphery of this pump and effect a result comparable to that produced by the baffles 12 of Fig. 1. In this instance, however, the baffles are supported by a suitable base 22 mounted on rods or the like 23. Each of the baffles is suitably spaced from its adjacent ones so that the spray whirled from the periphery of the pump will contact with the baffles and be atomized in the form of a fog or mist 21^a. The baffles shown in Fig. 2 and more clearly illustrated in Fig. 5 may be in the form of two concave surfaces meeting at one edge, the edge being comparatively sharp and directly in the path of the spray coming from the pump. It has been found that by making the baffles concave from the outer top and bottom edges to the middle meeting edge, and also from the side edges, a concave surface will be produced substantially throughout the inside of the baffles and effect a more thorough atomization of the impinging spray. It is apparent that baffles 12^a of Fig. 2 may not only be positioned about one of the pumps but may be arranged to cooperate with any of the pumps in any desired arrangement. Thus, the baffles may be positioned about the peripheries of successive pumps or may be positioned to break up alternate sheets of spray, etc. For many purposes it is highly desirable to have a combination wherein alternate strata of coarse and fine spray, or spray and fog, are produced in a device using a multi-stage pumping arrangement.

100 105 110 115 120 125 130 In the operation of the device of Fig. 2, incoming air or gas through intake ports 17^a is drawn upwardly by fan 13 through fog 21^a and then through sheets of spray 20 to be exhausted from the device through openings 18^a. The gases will thus first pass through the fog and then through the sheets of spray, the entrained moisture being precipitated or flocculated by contact with the spray.

135 In Fig. 3 is illustrated in greater detail the production of spray and mist by a pump

in combination with auxiliary atomizing baffles. The liquid is whirled from periphery 24 in the form of a spray 25. Upon contacting with radially disposed baffles 26, further breaking up takes place to produce mist or fog 27. This method can be used in the multi-stage type as well as in the specific arrangements shown in Figs. 1 and 2 to produce alternate strata of coarse and fine spray or mist in any desired combination.

In Fig. 4 pump 28 is formed with an apron 29 integral with the periphery of the pump. With this type of pump, moisture is drawn upwardly on the inner surface and over edge 30 of the apron. Edge 30 may be made thin so that the liquid thrown from the edge will be broken up to a greater degree of fineness than is usually obtained by whirling from the periphery of a comparatively flat distributing surface.

In Fig. 5 the pump 31 is of a design in which liquid may be drawn upwardly on both inner and outer surfaces. This pump also has an apron 32 formed integral with the periphery. The one pump will, therefore, throw a plurality of sheets of spray. As shown, auxiliary baffles 33 are positioned adjacent the apron so that the sprays coming from them may be further broken up into mist or fog 34. It is obvious that the baffles may be arranged so that instead of the sprays contacting with the concave surfaces 35 they may each contact with a knife edge 36 suitably designed and positioned to meet a sheet of spray and cause its further atomization. Furthermore, the pump of Fig. 5 may be arranged so that but one of the sheets of spray is further atomized and the other left undisturbed. As a result a sheet of spray and a strata of fog will be formed to produce a result comparable to that effected in a multi-stage device.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a device for humidifying gases, pumps comprising baffles, means for rotating the pumps, a liquid reservoir in the device, means whereby some of said pumps serve to produce a moisture condition approximating fog, and other of said pumps produce a mois-

ture condition approximating spray, the fog and spray forming a series of strata superposed one above the other.

2. Means for increasing the moisture content of gases, comprising a container having a reservoir for liquid, pumping means adapted to rotate in the liquid and produce spray, baffle means for breaking up the spray into moisture of finer particles, said baffle means being adapted to be positioned to permit gases to be drawn through the container and contact first with the finer spray and then pass through the coarser spray, said spray being in the form of sheets of moisture, each of which is substantially of uniform consistency and said container walls providing means for returning to the reservoir the entrained moisture precipitated due to contact of the gases with the coarser spray.

3. A device of the character described having a pump, an apron integral with the periphery of the pump and presenting a plurality of distributing edges for liquid supplied by the pump, said pump being designed to supply a plurality of sheets of water to the apron, said apron being adapted to produce sheets of water in the device at different levels.

4. A device of the character described having a pump, an apron integral with the periphery of the pump and presenting a plurality of distributing edges for liquid supplied by the pump, said pump being designed to supply a plurality of sheets of water to the apron and means comprising baffles adjacent the distributing edges of said apron for breaking the liquid received therefrom into finely divided particles.

5. A device of the character described comprising a container for liquid a pump within said container, an apron integral with the periphery of the pump and presenting a plurality of distributing edges for liquid supplied by said pump, said pump being designed to supply a plurality of sheets of water to the apron, an annular deflector plate extending inwardly from the wall of said container and means for admitting air within said container below said deflector plate and routing it through the sheets of liquid created by said apron.

In testimony whereof I affix my signature,
S. C. CUTLER.
